Joseph C. Lichtenberger Inventor
By his Attorney
Charles H. Wilson

UNITED STATES PATENT OFFICE.

JOSEPH A. LICHTENBERGER, OF NEW YORK, N. Y., ASSIGNOR OF ONE-THIRD TO
THOMAS E. CHIGOY AND ONE-THIRD TO CHARLES H. WILSON, BOTH OF NEW
YORK, N. Y.

DRAWER-KNOB-FASTENING MEANS.

1,405,528.

Specification of Letters Patent. Patented Feb. 7, 1922.

Application filed April 26, 1919. Serial No. 293,037.

To all whom it may concern:

Be it known that I, JOSEPH A. LICHTENBERGER, residing at New York, in the county and State of New York, have invented certain new and useful Improvements in a Drawer-Knob-Fastening Means, of which the following is a specification.

This invention relates to improvements in drawer pulls, that is to say, the knobs or handles usually attached to drawers or doors of furniture, by means of which they are opened or closed.

One of the objects of the invention is to provide a device of the above character which can be attached or mounted upon its support in such a way that it cannot work loose or pull out.

Another object of the invention is to provide a device of the above character, wherein the use of the usual attaching screws is eliminated, and which may be readily mounted upon the article of furniture upon which the same is to be used.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claim.

In the accompanying drawing, wherein I have illustrated preferred embodiments of my invention:

Figure 1 is a sectional view taken through the front wall of a drawer, showing my improved attaching device in elevation.

Figure 2 is a sectional view taken on line 2-2 of Figure 1.

Figure 3 is a view in perspective, showing a slightly modified form of shank.

Figure 4 is a similar view, showing the manner in which the tangs of the attaching device are driven into the grain of the wood.

Figure 5 is a view in perspective of the shank shown in Figure 1; and

Figure 6 is a view in elevation, showing the attaching means employed in the construction illustrated in Figures 3 and 4.

Referring now to the drawing, wherein similar reference characters refer to similar parts throughout the several views thereof, the reference numeral 1 denotes a handle

or knob, which in the present instance is made of moldable material, said handle or knob being molded about a cylindrical post or shank 2, the latter being provided with a recess 3, into which the moldable material enters whereby the knob or handle is more firmly fixed upon the shank.

The shank 2 is adapted to be inserted in an aperture 4, provided in the front wall of the drawer, door, or other movable part of furniture to which the knob is to be applied.

Formed in the inner end of shank 2, in the present instance, are curved slots 5 and 6 respectively, which lead from the inner end 7 of the shank inwardly and laterally, so that said slots terminate, as at 8 and 9 in the side walls of the shank.

The reference numeral 10 denotes a button, to which are attached the tangs 11 and 12, which are preferably formed of slightly tempered steel, the tangs being pointed at their ends, as indicated at 13 and 14 in the dotted lines in Figure 2.

In the embodiment shown in Figures 1, 2 and 5, it will be noted that the slots 5 and 6 are located entirely within the body of the shank. These slots are curved so that when the shank 2 is in the position shown in Figure 1, the tangs 11 and 12 may be inserted in the ends of the slots, whereupon they may be driven inwardly in said slots, which operate to distort the shank, so that when they emerge from the lateral openings or mouths of the slots they will be directed laterally into the wood forming the wall of the particular part of furniture to which the knob is to be attached. It will be noted that these shanks are driven substantially parallel with the grain of the wood.

In the embodiment shown in Figures 3, 4 and 6, slots 15 and 16 are provided in the inner end of the shank 2. These slots, however, are open-ended as well as open-sided, as shown in Figures 3 and 4. In this construction a head 17, having the tangs 18 and 19, is provided so that when the latter are inserted in the outer ends of the slots, and driven inwardly therein, the parts take the position substantially shown in Figure 4, the tangs 18 and 19 entering the wood surrounding the opening in the drawer or door, in the manner illustrated in Figure 1. In the said figure it will be observed that the shank 2

occupies but a portion of the aperture 4, and it is believed to be plainly discernible from the drawing that when the bifurcated headed fastener is completely driven into place, the 5 engagements of the tangs with the slots and wall as explained will forcibly pull the shank into the aperture and hold the knob firmly to the wall.

Thus it will be seen that I have provided 10 a device of the above character, which can neither pull out nor work loose. In fact, pulling on the knob or handle operates to further tighten it in its support.

It will be understood that the device may 15 be easy to remove by inserting an instrument under the head 10, and prying it inwardly, whereby the tangs are readily removed from the slots of the shank.

As many changes could be made in this 20 construction without departing from the scope of the following claim, it is intended that all matter contained in the above description or shown in the accompanying

drawing shall be interpreted as illustrative only and not in a limiting sense.

Having thus described my invention what I claim as new and desire to secure by Letters Patent is:

In a knob fastener, the combination with a penetrable wall having an aperture, of a 30 knob provided with a solid shank having oppositely inclined slots opening through the end and the side wall of the said shank, and a driven fastener comprising a single plate bifurcated to form separated tangs having 35 sharpened extremities, the said tangs being arranged to correspond in position with the slots and to pass through the slots into said wall to hold the knob to the wall.

In testimony whereof I affix my signature 40 in the presence of two witnesses.

JOSEPH A. LICHTENBERGER.

Witnesses:

THOMAS E. CHIGOR,
MARCY LEVY.
